CLAIM

The ornamental design for solar energy collector or the like, substantially as shown.

DESCRIPTION

FIG. 1 is a front elevational view showing a solar energy collector or the like showing my new design;
FIG. 2 is a rear elevational view thereof;
FIG. 3 is a right side elevational view thereof;
FIG. 4 is a top plan view thereof;
FIG. 5 is a bottom plan view thereof; and
FIG. 6 is a bottom and right side front perspective view thereof.

FIG. 1

FIG. 4

FIG. 5

FIG. 2

FIG. 3
